[57] CLAIM

The design for connector for two tubes in playground
structures, as shown and described.

DESCRIPTION

FIG. 1 is a perspective view of the design for the connector
for two tubes in playground structures of this invention.

FIG. 2 is a side elevational view of the design for the
connector, the opposite side of which is a mirror image.

FIG. 3 is a top plan view of the design for the connector.

FIG. 4 is a bottom plan view of the design for the connector.

FIG. 5 is a rear elevational view of the design for the
connector; and,

FIG. 6 is a front elevational view of the design for the
connector.
